Des. 187,278
Patented Feb. 23, 1960

187,278

PORTABLE TELEVISION STAND

Walter Gusdorf, Brentwood, Mo.

Application July 27, 1959, Serial No. 56,952

Term of patent 7 years

(Cl. D33—3)

Fig. 1 is a perspective view from the front of a portable television stand showing my new design;

Fig. 2 is a perspective view of the portable television stand of Fig. 1 showing the opposite end thereof;

Fig. 3 is an end elevation; and

Fig. 4 is a sectional view taken along line 4—4 in Fig. 1.

I claim:

The ornamental design for a portable television stand, substantially as shown.
